UNITED STATES PATENT OFFICE.

FREEMAN A. TABER, OF BOSTON, MASSACHUSETTS.

LAMP.

SPECIFICATION forming part of Letters Patent No. 278,373, dated May 29, 1883.

Application filed March 5, 1883. (No model.)

To all whom it may concern:

Be it known that I, FREEMAN AUGUSTUS TABER, a citizen of the United States, residing at Boston, in the county of Suffolk and State of Massachusetts, have invented certain new and useful Improvements in Lamps; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to means for carrying the air which supports combustion by an indirect or tortuous course in its passage to the wick-tubes, in order to lessen liability of the flame being extinguished by strong or irregular drafts of wind, and also to supply an abundant quantity of air to support combustion at the burner.

My invention further consists in the peculiar construction of the lamp-body, whereof the air is taken in at the top and caused to descend to the bottom thereof and return to the top before being admitted to the burner, substantially as hereinafter described.

The drawings accompanying this specification represent, in Figure 1, a vertical section, and in Fig. 2 a horizontal section, of a lamp containing my improvements.

In said drawings, A represents the oil-fount of a lamp adapted to burn hydrocarbon oils or fluids, such oil-fount being inclosed within an outer case, B, of somewhat larger diameter and length, leaving a space, C, between the two for passage of air, as hereinafter explained. As small quantities of oil are liable to drip between the fount and its inclosing-case and collect in the bottom D of the latter, I preferably connect such bottom to the sides in such manner as to permit of its being readily removed to allow of cleaning. In the present instance the bottom D is simply a shallow cup tightly inclosing the bottom of the case B. The burner is shown at E as of ordinary construction, and screws into the filling-orifice of the oil-fount in the usual manner.

In carrying out my invention I surround the lower part of the burner E and its air-sup-

plying orifices a a, &c., with a hood, F, which connects the upper part of the burner with the lamp-body in such manner as to prevent direct access of air to the said air-inlets a a, thereby protecting such inlets, and indirectly the flame of the burner, from liability of being extinguished by sudden drafts of air. To supply the burner with the requisite amount of oxygen to support the combustion of the oil, I divide the space C, as shown in Fig. 2 of the drawings, into two parts by vertical partitions b b, which extend from the top nearly to the bottom of such space, between the oil-fount and case B, and I form in the bottom of the hood F an aperture, c, which opens communication between the interior of such hood and one side, d, of the space C, as shown in Fig. 1 of the drawings, such side d being in reality a flue. The flue d is covered at top to prevent entrance of air directly from the atmosphere to the burner through the aperture c, while the opposite side or flue, e, of the space C is open to the atmosphere, but shut off from communication with the burner by the hood F. The upper part of the passage or flue e is covered by a foraminous or reticulated shield, f, through the interstices of which the air passes in entering the said flue. This foraminous shield f protects the interior of the flue e, and indirectly the burner, from sudden fluctuations or gusts of air outside of the lamp.

Under the above construction of a lamp air enters the mouth of the flue e by and through the reticulated shield f, descends such flue outside of the hood F, and passes across the bottom of the oil-fount and ascends the flue d into the interior of the hood F, and from thence to the burner by the air-inlets a a, &c. This construction of a lamp not only prevents extinguishment of the flame by undue drafts of air, but provides ample supply of oxygen to the burner.

I claim—

1. A lamp constructed as herein described, consisting of the oil-fount A, inclosing-case B, burner E, hood F, preventing direct passage of air to the burner, and the flues d and e, the flue e communicating directly with the atmosphere and supplying the flue d, and the latter communicating with the interior of the hood, 100

and with the burner by the aperture *c* in such hood, substantially as described.

2. The combination of oil-fount *A* with in-closing-case *B*, having removable bottom *D*, burner *E*, hood *F*, preventing direct passage of air to the burner, and being provided with aperture *c*, the flue *e*, communicating, directly with the atmosphere, and the flue *d*, supplied

by flue *e*, and supplying the burner through aperture *c*, substantially as set forth. 10

In testimony whereof I affix my signature in presence of two witnesses.

FREEMAN AUGUSTUS TABER.
